UNITED STATES PATENT OFFICE.

THOMAS I. DUFFY, OF OAK PARK, ILLINOIS, ASSIGNOR TO STEWART-WARNER SPEEDOMETER CORPORATION, OF CHICAGO, ILLINOIS, A CORPORATION OF VIRGINIA.

LAMP-MOUNT FOR PROJECTORS.

1,300,360.

Specification of Letters Patent. Patented Apr. 15, 1919.

Application filed June 19, 1917. Serial No. 175,624.

To all whom it may concern:

Be it known that I, THOMAS I. DUFFY, a citizen of the United States, and a resident of Oak Park, in the county of Cook and the State of Illinois, have invented certain new and useful Improvements in Lamp-Mounts for Projectors, of which the following is a specification, reference being had to the accompanying drawings, forming a part

10 thereof.

The purpose of this invention is to provide simple and inexpensive means for mounting and adjusting an electric lamp bulb in relation to the focusing member, 15 such as the reflector, of a lantern of the projector type, as for example, a headlight or a search light. The invention consists of the features and elements described and shown in the drawings, as indicated by the 20 claims.

In the drawings:

Figure 1 is a side elevation of a lantern body with certain interior parts shown in section to indicate details of construction of the lamp mounting means.

Fig. 2 is a sectional view of the lamp mounting means taken axially with respect to the lamp and substantially at right angles to the section of Fig. 1, as indicated by line 0 2-2, on Fig. 1.

Fig. 3 is a detail section taken trans- 5 axially, as indicated at line 3-3, on Fig. 1.

Fig. 4 is a detail section taken as indicated at line 4-4 on Fig. 1.

Fig. 5 is a detail section of the switch lever.

Fig. 6 is a detail view partly in section and with parts broken away to show the mounting means for the reflector.

Fig. 7 is a developed section on an enlarged scale taken as indicated at line 7-7 on Fig. 6.

Fig. 8 is a side elevation of a modified form of focusing means.

In the embodiment of this invention shown in the drawings, the lantern casing or body, 1, is provided with a fixedly mounted reflector, 2, which may be understood as a focusing reflector, so that the incandescent filament, 3, of the lamp bulb, 4, is preferably in a form in which its luminous portion is disposed as nearly as possible at a single point and in which this incandescent point or source of light should be substantially at the point in space which constitutes the

focus of the reflector, 2. Since the filament of the lamp cannot be arranged with absolute accuracy with respect to the lamp bulb and base, 5, it is desirable to provide means for adjusting the lamp bodily with respect 60 to the reflector, 2, so as to bring its incandescent filament, 3, to the focal point of the reflector.

To arrange for such adjustment, there is provided a mounting block, 6, preferably of insulating material to which the reflector, 2, is secured by the engagement of three lugs, 7, of a mounting ring, 8, with securing screws, 9, in bosses, 10, of the block, 6. The material of the reflector, 2, immediately 65 surrounding its central aperture, is crimped as indicated in Figs. 6 and 7 to form teeth, 11, against which the flange, 12, of the ring, 8, is firmly pressed, forming a permanent 70 union between the reflector, 2, and the ring, 8.

The block, 6, is formed with a bore co-axial with the central aperture of the reflector, 2, and serving as a guide for a lamp carrier in the form of the cylindrical tube, 13, slidably mounted in said bore. The tube, 13, is secured against rotation in the bore of the block, 6, by its outwardly turned lug, 14, fitted in a longitudinal groove, 15, of the block, 6. The lamp base, 5, is secured 80 in the tube, 13, by the usual bayonet lock, causing the L-shaped slots, 16, in diametrically opposite bores of the tube wall for engaging radially extending pins, 17, on the lamp base, 5. The terminal portions of the 85 L-slots, 16, are slightly offset to provide notches, 18, tending to lock the lamp base, 5, against rotation when the pins, 17, are engaged therein. The axial pressure required to maintain this engagement is supplied in the form of spring contact members 19 acting against the extreme inner end of the lamp base, 5, as indicated in Fig. 1.

The lamp carrier tube, 13, being axially 100 slidable in the mounting block, 6, is rendered definitely adjustable therein by means of a cam plate, 20, rotatably secured to the rear face of the block, 6, by means of two screws, 21, engaging segmental slots, 22, in said plate, 20, together with a radially-extending 105 tongue or lug, 23, near the rear end of the tube, 13, overlapping and engaging the cam face, 24, of the plate, 20. Said face, 24, is in the form of a curved incline formed upon the plate, 20, at a portion immediately ad- 110

5 jacent its central aperture, and therefore immediately adjacent the portion of the tube, 13, extending through said aperture. The lug, 23, is held in engagement with the cam face or incline, 24, by the spring pressure of the yielding conductor members, 19, exerted against the end of the lamp base, 5, and transmitted through the pins, 17, and notches, 18, to the tube, 13. Thus, while 10 these yielding conductor springs, 19, tend to force the lamp in one direction, that is, outwardly with respect to the reflector, 2, said lamp may be withdrawn in the opposite direction by partial rotation of the cam plate, 20, and when the desired location of the incandescent filament, 3, is thus determined, the parts may be secured in this adjusted position by tightening the heads of screws, 21, against the face of the plate, 20, adjacent 15 to the slots, 22. It will be seen that this in no way interferes with the removal and replacement of the lamp, 4, but upon renewal of said lamp the focus may be readjusted if necessary.

20 25 The spring conductor members, 19, are secured to the mounting block, 6, by screws, 25, as shown in Fig. 1, and one of the lead wires, 26, is connected to its corresponding conductor, 19, by securement under the head of one 30 of the screws, 25. The other lead wire, 27, is attached by a binding screw, 28, to the spring contact arm, 29, of a switch device, having a switch lever, 30, whose collar portion, 31, encircles the cylindrical body of 35 the mounting block, 6, being retained thereon by engagement of certain portions in grooves formed between the bosses, 10, of the block, 6, and the forward face of the flange, 32, of said block, on whose rear face 40 the focusing cam plate, 20, is mounted. The switch lever, 30, is mounted for limited rotation whose extent is determined by a 45 slot, 33, in the lantern casing, 1, through which the handle portion, 34, of the switch lever projects. The contact spring, 29, being secured to the arm of the lever, 30, is bent to extend transversely through an aperture, 35, therein for contact of its end portion with a part of that conductor spring, 19, to which no lead wire is connected, thus 50 serving to complete the electric circuit. When the switch lever, 30, is swung or rotated to move its contact member, 29, away from the conductor spring, 19, the end of 55 said contact member, 29, drops into a notch, 36, in the flange, 32, of the block, 6, thus preventing the switch lever from being jarred back into position for electrical connection of the members, 19 and 29, but by 60 virtue of the yielding nature of the contact spring, 29, readily permitting said lever to be moved into such position if desired.

65 For purposes of assembling the collar portion, 31, of the switch lever, 30, is formed with three notches, 37, extending radially

from a central aperture and designed to fit over the bosses, 10, on the mounting block, 6. The notches, 37, being registered with the bosses, 10, the collar is slipped down against the flange, 32, and then rotated to its position of use in which the notches, 37, will never register with the bosses, 10, so that when the block, 6, is mounted in the casing, 1, whose slot, 33, limits the rotation of the switch lever, 30, said lever is securely mounted on said block and cannot come out of the groove, in which it rotates. Similarly, a notch, 38, in the cam plate, 20, permits fitting it over the end of the tube, 13, without interference from the lug, 23; but when rotated to normal position of use and secured by the screws, 21, said notch, 38, of the plate, 20, will not again register with the lug, 23, and therefore will not permit disengagement of the parts.

70 To prevent short-circuiting of the conductor springs, 19, by the metallic lamp-carrying tube, 13, the apertures, 39, in said tube through which said conductor springs extend for contact with the rear end of the 75 lamp base, 5, are made slightly wider than said springs, and the springs themselves are snugly housed in notches, 40, in the flange, 32 of the block, 6, with just sufficient clearance to permit their easy yielding play upon 80 movement of the lamp base, 5, with respect to the block, 6. Since the tube, 13, is secured in the block, 6, against rotation by engagement of the lug, 14, in the groove, 15, there is no opportunity for the walls of the apertures, 39, to come into contact with the edges of the conductor springs, 19. It is also desirable to provide clearance notches, 41, in the central aperture of the switch lever collar, to prevent contact of said collar with 85 the secured portion of the conductor springs, 19, which lie in grooves or notches in the cylindrical surface of the mounting block, 6.

90 In Fig. 8 there is shown a modification 95 of the structure in respect to the means for adjusting the lamp axially in its socket. In this modification the insulating mounting block, 6, has its rear face formed with two cam slopes, 6^a, 6^b, and intervening abrupt shoulders, 6^c. On the rearwardly-protruding end portion of the sleeve, 13, which constitutes the lamp socket, there is mounted an annular cam plate, 50, having cam slopes and shoulders corresponding to the slopes and shoulders of the rear face of the insulating block, so that rotation of the cam plate on the block, 6, causes the cam plate to be moved axially; and the sleeve, 13, is provided at its rear end outside the cam plate with an exteriorly-projecting flange, 6^a, between which and the cam faces of the insulating block, said cam plate is retained. It will be seen that the rotation of the cam plate in one direction retracts the lamp socket or sleeve, 13, carrying the lamp with 100 105 110 115 120 125 130

it, and its rotation in the opposite direction permits the lamp socket to be thrust forward by the reaction of the spring contact pieces, 19.

5 I claim:

1. In a light projector a focusing member, an incandescent lamp bulb, a guide fixed with respect to the focusing member, a lamp carrier mounted to move on said guide along 10 the axis of said focusing member, a yielding conductor engaging the base of the lamp in the carrier and arranged to force said lamp and carrier in one direction along said axis, and a cam device associated with the guide 15 and adjustable for moving said carrier in the opposite direction.

2. In a light projector a focusing member, an incandescent lamp bulb, a mounting block fixed with respect to the focusing member, 20 a lamp carrier guided for movement through said block along the axis of the focusing member, a yielding conductor engaging the base of the lamp in the carrier and arranged to force said lamp and carrier 25 in one direction along said axis, a cam plate rotatively mounted on the rear face of said block, and means on the carrier engaged by said plate for adjustment of said carrier in opposition to the yielding conductor.

30 3. The combination of a centrally apertured focusing reflector, a centrally bored mounting block secured at the back of said reflector, a socket tube slidably carried in the bore of said block, a cam plate mounted for rotation on the rear face of the block, yielding means tending to force the socket in one direction, and means on the socket engaged by said cam plate for adjustment of said socket by rotation of said plate.

40 4. The combination of a focusing member, a socket member mounted for adjustment along the axis of said focusing member, a lamp carried in said socket member, the lamp base having a contact area on its end, 45 a yielding conductor in contact with said area, and a cam engaging the socket member adapted to adjust and retain said member in opposition to the pressure of said yielding conductor.

50 5. The combination of a focusing member, a socket member mounted for adjustment along the axis of said focusing member, a lamp carried in said socket member, the lamp base having a contact area on its end, 55 a yielding conductor in contact with said area, a cam plate mounted to rotate in a plane perpendicular to the axis of the focusing member and having a bearing face inclined to said plane, and a follower on the 60 socket member engaging said bearing face of the cam.

6. The combination of a focusing member, a socket member mounted for adjustment along the axis of said focusing member, a 65 cam plate mounted to rotate in a plane per-

pendicular to the axis of the focusing member having a bearing face inclined to said plane, a follower on the socket member engaging said bearing face, and yielding means for maintaining such engagement. 70

7. In combination with a focusing member, a socket tube and a mounting block in which said tube is guided for movement along the axis of the focusing member, a lamp in the tube having a contact area on 75 the end of its base, the tube being laterally slotted, a yielding conductor finger extending through the slot of the tube in contact with the said area of the lamp base and exerting a pressure thereon tending to move 80 the tube one way through the mounting block, and means on the block for adjusting and retaining said tube in opposition to such pressure.

8. In combination with a reflector an insulating mounting block, a lamp socket in the form of a sleeve extending through said block and guided for longitudinal movement therein, said socket having means for engaging a lamp base therewith, the sleeve 85 having an exteriorly projecting flange at its rear end, an annular member mounted on the sleeve and adapted to be rotated thereon, having a cam slope seated upon a corresponding slope of the insulating block, said 90 annular member being engaged under the flange of the sleeve for crowding said flange away from the said slope on the block when the annular member is rotated in one direction about the sleeve, and yielding means 95 tending to oppose the crowding movement of the sleeve.

9. In combination with a reflector an insulating mounting block, a lamp socket in the form of a sleeve extending through said 100 block and guided for longitudinal movement therein, said socket having means for engaging a lamp base therewith, the sleeve having an exteriorly projecting flange at its rear 105 end, an annular member mounted on the sleeve and adapted to be rotated thereon, having a cam slope seated upon a corresponding slope of the insulating block, said 110 annular member being engaged under the flange of the sleeve for crowding the flange away from said slope on the block when the annular member is turned in one direction about the sleeve, and spring contact fingers 115 mounted on the block extending into the sleeve for contact with the lamp base reacting thereagainst in the direction for forcing the flange of the sleeve toward said block.

10. In a light projector in combination with a reflector a mounting block of cylindrical form with a plurality of radially projecting and circumferentially spaced bosses at one end for attachment to the reflector, and a flange at the other end, a switch lever having a flat collar with a circular aperture and a plurality of radial 125 130

notches in the outline of said aperture spaced to register with the bosses of the mounting block for assembly thereon, said block having a groove between each boss 5 and the aforesaid flange dimensioned to accommodate the thickness of the flat collar of the switch lever to permit rotation of the lever on the block and a casing having a segmental slot to receive the handle of the 10 lever and so limiting its rotation as to prevent the notches from registering with the bosses of the block when the parts are thus assembled.

11. In a light projector a reflector with a 15 central aperture to receive a lamp base, a

mounting block for such lamp base, and means for attaching said block to the reflector comprising a collar with parts secured to the block and a sleeve portion extending through the aperture of the reflector 20 with flanges pressed against the opposite faces thereof, the material of the reflector at the periphery of its aperture being crimped to form teeth for securely engaging the flanges of the collar to effect a non- 25 rotative connection therewith.

In testimony whereof I have hereunto set my hand this 29th day of May, 1917.

THOMAS I. DUFFY.
